UNITED STATES PATENT OFFICE.

ALBERT HEINZE, OF NEW HAVEN, CONNECTICUT.

PAINTING-MACHINE.

SPECIFICATION forming part of Letters Patent No. 651,166, dated June 5, 1900.

Application filed March 15, 1900. Serial No. 8,825. (No model.)

To all whom it may concern:

Be it known that I, ALBERT HEINZE, a citizen of the United States, residing at New Haven, in the county of New Haven and State of Connecticut, have invented certain new and useful Improvements in Painting-Machines; and I do declare the following to be a full, clear, and exact description of the invention, such as will enable others skilled in the art to 5

the judgment of the operator, who has full view of the deposit as it forms on the surface being treated, the machine being held in one hand by grasping the handle L while it is being operated to cause the deposit of pigment or ink by operating the crank C with the other hand.

While I have described my construction in connection with a reservoir for receiving the liquid pigment, I may use in connection with the pigment-rollers simply an ordinary paint-brush to coat the pigment-rollers with the pigment that is to be imparted to the rotary brushes and thrown upon the spatterer to be therefrom distributed to the surface to be treated. While the reservoir for receiving the liquid paint is desirable and very likely preferable to most users of the machines, yet it is not absolutely essential, as the absorbent rollers can be painted or coated with liquid pigment by means of a hand paint-brush, so that, if desired, the reservoir may be dispensed with, and I also use my painting-machine in this latter form.

Although I have described the construction and operation of my painting-machine in the form best known to me, it is obvious that many minor changes might be made in the construction of the same without departing from the character of the invention, and I do not confine myself to the exact construction herein described and illustrated.

Having thus fully described my invention, what I claim, and desire to secure by Letters Patent, is—

1. In a painting-machine of the class described, the combination with the casing having a discharge-opening in its bottom; of the absorbent rollers; the rotating brushes beneath them and geared thereto; the spatter bars or rods engaging said brush-rollers; the valved pigment-reservoir above said absorbent rollers and means for holding the casing over the surface receiving treatment and

means for imparting motion to said geared 45 rollers; substantially as specified.

2. In a painting-machine of the class described, the combination with the open-bottom casing; the valved reservoir at its upper portion; the absorbent rollers beneath said 50 valved reservoir; rotary brushes beneath said absorbent rollers; gearing connecting said absorbent rollers and said rotary brushes; means for imparting motion to said rollers and brushes; and spatter bars or rods supported beneath and in contact with said rotary brushes by an adjusting-rod connected with said casing by an adjusting-nut for regulating and varying the positions of the spatter bars or rods and rotary brushes and thereby varying the grain or texture of the deposit upon the surface treated; substantially as specified.

3. In a painting-machine of the class described, the combination with the casing, of 65 the crank-operated absorbent rollers; the brush-rollers beneath said absorbent rollers; the adjustable spatter bars or rods supported adjustably beneath said brush-rollers; and the valved reservoirs supported above said 70 absorbent rollers and gearing connecting said absorbent rollers with said brush-rollers; substantially as specified.

4. In a painting-machine of the class described, the combination with the casing, of 75 the crank-operated absorbent rollers; the brush-rollers beneath said absorbent rollers; the adjustable spatter-bars beneath said brush-rollers; and gearing connecting said absorbent rollers and said brush-rollers; substantially as specified.

In testimony whereof I have hereunto set my hand in presence of two subscribing witnesses.

ALBERT HEINZE.

Witnesses:

HARRY C. TOLLES,
LECHAUD CANNON.
